UNITED STATES PATENT OFFICE.

LOUIS J. HULLA, OF ONAWAY, MICHIGAN, ASSIGNOR OF ONE-HALF TO HENRY LIPSHIELD, OF ONAWAY, MICHIGAN.

FAUCET.

Application filed May 5, 1923. Serial No. 637,000.

To all whom it may concern:

Be it known that I, LOUIS J. HULLA, a citizen of the United States, residing at Onaway, in the county of Presque Isle and State of Michigan, have invented new and useful Improvements in Faucets, of which the following is a specification.

This invention relates to plumbing fixtures, particularly to faucets, and has for its object the provision of a novel faucet which may be used in the ordinary manner and which is also capable of use as a drinking fountain, inasmuch as it is provided with a movably mounted nose piece which may be turned to direct a small stream of water upwardly in a manner common to drinking fountains, so that it will be unnecessary to keep a cup or glass around a sink or other place in order to enable a person to secure a drink of water.

An important object is the provision of a device of this character which is provided with means whereby the stream of water issuing from the faucet will automatically be cut down when the nose piece is turned to upwardly extending position for use as a drinking fountain, while at the same time the flow is unobstructed and may be of full force when the nose is in its normal or downwardly extending position.

Still another object is the provision of a device of this character which will be very sanitary, and consequently most conducive to health, while at the same time it will be simple and inexpensive to manufacture, easy to control and operate, and a general improvement in the art.

With the above and other objects and advantages in view the invention consists in the details of construction to be hereinafter more fully described and claimed and illustrated in the accompanying drawings, in which:

Figure 1 is a side elevation of a faucet constructed in accordance with my invention,

Figure 2 is a longitudinal section therethrough showing the nose in normal position,

Figure 3 is a cross section on the line 3—3 of Figure 2,

Figure 4 is a view similar to Figure 2 but showing the nose in upwardly extending position,

Figure 5 is a cross section on the line 5—5 of Figure 4.

Referring more particularly to the drawings I have shown my faucet as comprising the usual body 10 which may be suitably finished, which may be of any desired material and of any conventional or preferred size and shape. At one end this body is formed with an angular portion 11 and a threaded extension 12, the latter being for the purpose of making connection with a water pipe and the former being for the purpose of affording a grip for a wrench or other tool to effect connection of the device. The other end of the body terminates in a tubular outlet conduit 13 which is externally threaded as shown. Within the body is a valve seat 14 adapted to be closed by a valve 15 on a stem 16 which is journaled through a removable cap 17 and which carries an operating handle 18. This stem has an enlarged portion 19 formed with a spiral groove or thread 20 whereby the valve will be raised and lowered automatically when the stem is turned by means of the handle. The structure thus far described is old and well known and no novelty is claimed therefor, except that in so far as any modifications are necessary to adapt the device for connection with my attachment.

Within the outlet conduit 13 is a disk 21 formed with a hole 22 eccentrically thereof. The numeral 23 represents the outlet nose piece which is of substantially L-shape as is customary, but which is formed with a flange 24 engaged by a flange 25 on a slip nut 26 which is internally threaded for screwing engagement upon the outlet conduit 13. Within the slip nut is a packing gasket 27 of a resilient nature to make a water tight connection and prevent leakage at the joint. Located within that portion of the nose piece which is within the slip nut is a screen 28 which operates to remove sediment from the water and this screen must necessarily be made of some non-corrosive material. The inlet end of the nose piece is covered by a disk 29 formed with a hole 30. It should also be stated that the nose piece carries a projection 31 at its top which constitutes a handle facilitating turning the nose piece into either of its selected positions.

In the operation it will be seen that normally, that is when the nose piece is in its downturned position, the device is used in exactly the same manner as an ordinary 5 faucet. At this time the holes 30 and 22 in the disks 29 and 21 respectively are in absolute registration, so that the maximum flow of water may be had. When it is desired to use the device as a drinking fountain, it is 10 merely necessary that the operator grasp the handle 31 and turn the nose piece into its upwardly extending position. When the water is subsequently turned on by means of the handle it is quite apparent that a 15 stream thereof will be directed upwardly so that the drinker may place his mouth over the stream and quench his thirst without it being necessary to employ a cup, glass or other receptacle. When the nose piece is 20 thus turned upwardly, it is to be noted that the hole 30 registers only partly with the hole 22 so that the stream of water will be greatly cut down and the force diminished to prevent too strong a jet from being discharged. While it is not necessary it may 25 be preferable to provide a perforated porcelain nozzle 32 in the nose piece, which nozzle will be automatically kept clean by the flow

of water therethrough and there over so that the device will remain always in a satisfactory and sanitary condition. 30

While I have shown and described the preferred embodiment of the invention it is of course to be understood that I reserve the right to make such changes in the form, construction and arrangement of parts as will not depart from the spirit of the invention or the scope of the subjoined claim. 35

Having thus described my invention I claim: 40

In a faucet having a straight outlet conduit, a curved nose piece rotatably mounted upon the outlet conduit and disposable either in an upwardly or a downwardly extending position, a partition in the outlet conduit formed with a hole eccentrically thereof, a wall at the inlet end of the nose piece formed with an eccentric hole registering with said first named hole entirely when the nose piece is in downwardly extending position, the hole in the wall registering only slightly with the first-named hole when the nose piece is in upwardly extending position. 45 50

In testimony whereof I affix my signature.
LOUIS J. HULLA.
